UNITED STATES PATENT OFFICE.

CHARLES OSBORNE, OF NEW YORK, N. Y., ASSIGNOR TO THE WHITING MANUFACTURING COMPANY, OF SAME PLACE.

DESIGN FOR A SPOON, &c.

SPECIFICATION forming part of Design No. 20,636, dated March 24, 1891.

Application filed December 26, 1890. Serial No. 375,905. Term of patent 3½ years.

To all whom it may concern:

Be it known that I, CHARLES OSBORNE, a citizen of the United States, residing in New York city, in the county and State of New York, have invented and produced a new and original Design for Spoons, of which the following is a specification, reference being had to the accompanying drawing, forming a part thereof.

10 The drawing is a front view of a salad-spoon, showing my design, the spoon bowl and handle being shown in dotted lines.

15 The design may be produced upon other articles; but the view of one article is deemed sufficient to fully illustrate my design.

20 The leading feature of my design consists in the chased socket-like figure produced on the handle and having its lower end terminating in a calyx, from which springs an irregular fringe-like ornamentation which gradually terminates in the bowl, blade, or fork of the article.

25 A is the socket, which has scroll-like figures *a* produced thereon, the figures having their sides terminating in fringe-like figures

a', and the socket merges at its lower end into a calyx-like figure, from which spring the leaf-like figures *B*, which figures extend in irregular lines down into the bowl of the article and along the sides, the leaf-like figures 30 terminating at the edges and ends in irregular scroll-like figures *b*, and the leaf-like figures have the appearance of dying away in the bowl. The leaf-like figures *B* assume irregular fantastic shapes on the sides of the 35 bowl, as indicated at *C*, giving it the appearance of open-work, and the groundwork of the bowl has the appearance of being dinted, as shown at *D*. A corolla-like figure *E* is produced in the upper portion of the spoon-bowl, 40 which figure has the appearance of being enveloped by the leaf-like figures *B*.

I claim—

The design for spoons and similar articles herein shown and described.

CHARLES OSBORNE.
